SURGICAL SUTURE BRIDGE

Horace Frank McCarthy, North Andover, Mass., assignor
to Avco Corporation, Cincinnati, Ohio, a corporation
of Delaware

Filed July 27, 1959, Ser. No. 56,949

Term of patent 14 years

(Cl. D83—12)

FIGURE 1 is a perspective view of a surgical suture bridge employing my new design;

FIGURE 2 is a top plan view thereof;

FIGURE 3 is a side elevational view thereof with a portion of the arch being shown in section;

FIGURE 4 is an enlarged fragmentary cross-sectional view thereof taken on plane 4—4 of FIGURE 3; and

FIGURE 5 is an enlarged fragmentary cross-sectional view thereof taken on plane 5—5 of FIGURE 3.

I claim:

The ornamental design for a surgical suture bridge, as shown.
